UNITED STATES PATENT OFFICE.

FRANCIS VERSAVEL, GASTON VERSAVEL, RODOLPHE VERSAVEL, AND RAOUL VERSAVEL, OF ROUBAIX, FRANCE.

LET-OFF MECHANISM.

Application filed August 24, 1921. Serial No. 494,933.

To all whom it may concern:

Be it known that we, FRANCIS VERSAVEL, GASTON VERSAVEL, RODOLPHE VERSAVEL, and RAOUL VERSAVEL, citizens of the French Republic, and residents of Roubaix, France, have invented certain new and useful Improvements in Let-Off Mechanism, of which the following is a specification.

This invention relates to improvements in devices for automatically and uniformly winding off threads forming the warp in the manufacture of fabrics on weaving looms.

The object of our invention is to provide an improved device of this kind, wherein the usual cords and brake-disks serving to produce the resistance against the winding off of the threads are omitted.

A further object is to provide a device of the kind described, wherein the warp-beam upon which the threads are wound, instead of being journaled in stationary bearings or in grooves in the frame of the weaving loom, is journaled in movable levers in such a way that the warp beam with its warp threads is suspended and acts with its total weight upon all the threads to stretch the same, the warp-beam being still sufficiently free to be raised and lowered to a certain extent during the operation of the blades and the formation of the warp opening for the passage of the shuttle.

A further object of the invention is to provide an improved device of the kind described combined with a warp delivering device, capable of winding off the necessary length of threads without pull on the same, independently from the number of shoots or threads of the material used (silk, wool, cotton, jute and the like).

In order that the invention may be clearly understood, the same will be described with reference to the accompanying drawings, wherein:

Fig. 1 shows a side elevation of the improved device mounted on the levers carrying the whole system.

Fig. 2 is a plan view of the device;

Fig. 3 shows the lever which is opposite the lever shown in Figs. 1 and 2.

Fig. 4 shows a general view of the device mounted in place on a weaving loom.

Fig. 5 shows a bipartite collar intended to

be fixed on the beam to impart movement to the same.

Mounted on each frame of the loom (Fig. 1) at the suitable place and secured by means of bolts is a bearing *a*, provided at its upper inner part with an integral finger *a*¹, on which the lever is adapted to rest. The lower part of said bearing is provided with an integral angle piece *a*², to which the pivot pin 23 of the picker whip 21 is secured. The socket portion of said bearing *a* has a bore, in which the shaft *b* is journaled. Another similar bearing is provided for the opposite end of the shaft *b*. Keyed on one end of the shaft *b* by means of a key *c* is a lever *d*, on which are arranged the various parts of the system. Said parts comprise a pivot pin *e* on which the vertical lever *f* is pivoted. Said lever is actuated by means of a pitman *h* provided with a pivot-pin *g*. The reciprocating movement is produced by means of an eccentric disk (not shown in the drawings) mounted on any suitable rotating member of the loom. Pivoted connected to the upper end of the lever *f* by means of a pivot-pin *i* is a bar *j* provided with a nose *v* serving to actuate the pivot *g* by its reciprocating movement. Towards the outer end of the lever *d*, a part *k* is secured, said part being provided with a vertical axis *l* having a worm *x* and to the upper part of which a sleeve 1 is secured by means of a screw 2.

Pivoted on the axis *l* between said sleeve 1 and the ratchet wheel *m* is an angle piece *p*, having a bore for the reception of the pivot *q* held in place by means of a screw *r*. Mounted on the pivot *q* is a pawl *s* engaging and actuating the ratchet-wheel *n*. Passing around the socket of the piece *p* is a spring *t*, one end of which is held by a screw *u* on the part *m*. The opposite end of said spring is bent at right angles and bears against the piece *p* to bring the same back against the part *m* after each operation of the nose *v* of the bar *j*. Said part *m* also serves to hold in place the vertical axis *l* by means of screws 100 25 and 26, said axis *l* being also held at its lower part by means of screws 27 and 28. Secured to the lower part of the axis *l* is a small brake pulley 15, the braking action of which is obtained by means of a collar 105 lined with leather 14, adapted to be tight.

ened by means of a screw-threaded rod provided with a nut 17. Said rod is bent at 16 to a suitable length, so that the brake collar 14 will be held by the rod 13, for a slight 5 braking action. This brake serves to check the worm and is desirable on high speed looms for preventing a too rapid movement of the ratchet *n*. The worm *x* actuates the gear-wheel *y*, secured to the axis *z* and provided with an integral half-bearing for the 10 reception of the shaft of the warp-beam. A second half-bearing has a chamber or notch 4 and is held by means of bolts 29 and 30. Housed within said chamber 4 (after 6 and 15 7 has been tightened on the warp-beam) is the portion 5 of the bipartite collar 8. Engaged into the hole 12 is the hook of the rod 13. Between the screw-nuts 18 and 20, said rod 13 has a perforated ear 19 secured 20 to the whip 21 by means of a screw 22. Arranged on the whips 21 and 21' are weights 24 and 24' serving to stretch the warp. Secured to the opposite end of the shaft *b* by means of a key *c*¹ is a lever *d*' with its 25 bearing 9, bolts 10 and 11 and the hole 12¹, for the hook 13¹.

Besides the weight of the warp-beam with its material (warp-threads), the weight of the levers *d* and *d*' and the mechanism, there 30 are two whips 21 and 21' with adjustable weights 24 and 24' to hold the threads of the warp under tension as desired.

The warp-beam with its warp threads is placed into the bearings of the levers *d* and 35 *d*' and the warp threads are tensioned so that the mechanism is in the position shown in Fig. 1.

When the loom is in operation, an eccentric disk (not shown in the drawings) imparts a reciprocating movement to the pitman *h* and therefore to the bar *j*, pivot *q* and pawl *s*, the latter engaging and rotating the ratchet-wheel *n* step by step, the rotating movement of the wheel *n* being transmitted by the worm *x* to the wheel *y*, the movement of which produces the winding off of the warp through the agency of the collar *S*.

Should the pawl *s* deliver too great a 50 length of warp, the levers *d* and *d*' would be lowered. At the same time it would move the pivot *q* away so that the nose *v* of the bar *j* could no more reach it. Thus said pawl would remain inoperative until said 55 length of warp will be woven, when the levers *d* and *d*' will be moved back to their normal positions.

If however the delivery of warp threads is insufficient, the levers *d* and *d*' will be 60 raised and the pivot *q* moved nearer to the nose *v* of the bar *j*, so that the latter will act

longer on said pivot and the pawl *s*, whereby the ratchet-wheel *n* will be rotated to a greater number of teeth.

It will be understood that by the present 65 arrangement of the system the apparatus does not deliver more than the material which is necessary to the manufacture and it is the consumption of material or warp threads itself which automatically regulates 70 the winding off of material.

Having now fully described our said invention, what we claim and desire to secure by Letters Patent, is:

1. In a device for automatically and uniformly winding off the threads forming the warp of fabrics manufactured on weaving looms the combination with the warp-beam of movable levers to suspend said warp-beam so that the same acts with its full 80 weight on said warp-threads, and an automatic device controlled by the position of the beam through said levers for winding off the warp-threads.

2. In a device for automatically and uniformly winding off the threads forming the warp of fabrics manufactured on weaving looms, the combination with the warp-beam of movable levers adapted to receive said warp-beam so that the same is suspended thereon and acts with its full weight on said warp-threads, an automatic device for winding off the warp-threads, and means whereby the positive movement of the warp delivering device is regulated by the tension 95 of the warp threads incident to their consumption.

3. The combination with a warp beam, of levers for movably supporting said beam, and means adapted in operation to positively rotate the beam, the operation of said means being controlled by the position of said beam resultant from the tension of the warp threads incident to their consumption.

4. The combination of a warp beam, pivotally mounted levers in which said warp beam is swingingly supported, means reciprocated from an independent source, and mechanism operated by said means to rotate the beam, the effect of said mechanism 105 on the beam being controlled by the swinging movement of the levers.

In testimony whereof we have hereunto set our hand in the presence of two witnesses.
